UNITED STATES PATENT OFFICE

165,535

COMBINED SOLE AND HEEL UNIT FOR FOOTWEAR

Warren MacPherson, Cambridge, Mass.

Application August 11, 1949, Serial No. 4,421

Term of patent 14 years

(Cl. D7—5)

To all whom it may concern:

Be it known that I, Warren MacPherson, a citizen of the United States, residing at 151 Brattle Street, Cambridge, county of Middlesex, Commonwealth of Massachusetts, have invented a new, original, and ornamental Design for a Combined Sole and Heel Unit for Footwear, of which the following is a specification, reference being had to the accompanying drawings, forming a part thereof.

In the accompanying drawings,

Fig. 1 is a top perspective view of a combined sole and heel unit for footwear showing my new design; and

Fig. 2 is a transverse, sectional view taken substantially on the line 2—2, Fig. 1.

I claim:

The ornamental design for a combined sole and heel unit for footwear, as shown.

WARREN MACPHERSON.
